(57) **CLAIM**

The ornamental design for a wireless communication adapter, as shown and described.

DESCRIPTION

FIG. 1 is a top, front perspective view of a wireless communication adapter showing our new design.

FIG. 2 is a front view thereof.

FIG. 3 is a back view thereof.

FIG. 4 is a left side view thereof.

FIG. 5 is a right side view thereof.

FIG. 6 is a top plan view thereof.

FIG. 7 is a bottom plan view thereof.

FIG. 8 is a top, front perspective view of the wireless communication adapter of FIG. 1 shown in an extended state.

FIG. 9 is a front view thereof.

FIG. 10 is a back view thereof.

FIG. 11 is a left side view thereof.

FIG. 12 is a right side view thereof.

FIG. 13 is a top plan view thereof; and,

FIG. 14 is a bottom plan view thereof.
